Attorney

UNITED STATES PATENT OFFICE.

GEORGE J. S. COLLINS, OF PEORIA, ILLINOIS.

CYLINDER-BLOCK HOLDER.

1,851,232.

Specification of Letters Patent. Patented Aug. 31, 1920.

Application filed August 22, 1919. Serial No. 319,257.

To all whom it may concern:

Be it known that I, GEORGE J. S. COLLINS, citizen of the United States, residing at Peoria, in the county of Peoria and State of Illinois, have invented certain new and useful Improvements in Cylinder-Block Holders, of which the following is a specification.

This invention relates to cylinder block holders, that is to say, it belongs in that class of shop fixtures or appliances intended for the purpose of supporting at a workbench and at a convenient height, the casting which comprises the cylinders of a gasolene engine termed a cylinder block. Means are provided also for rotating the block in the support and for clamping the block in any desired position.

The object of this invention is the production of a cylinder block holder having parts of special construction and arrangement, whereby it is believed a particularly strong, cheap and easily operated adjustable support for the purpose stated results.

In the accompanying drawings the construction of each part and the arrangement of all the parts are illustrated. Figure 1 represents this invention shown partly in vertical section longitudinally, supported by a bench and holding a cylinder block. Fig. 2 is a front view of the carrier arm or triangular curved plate. Fig. 3 is a vertical cross-section taken upon the broken line 3—3 of Fig. 1, and drawn upon a somewhat larger scale. Fig. 4 is a top plan view upon the same scale of drawing as in Fig. 3, showing this invention without the trunnion pin and carrier.

Throughout the description and drawings the same letter is used to refer to the same part.

Considering the drawings, upon the bench A is supported a base a, upon which is erected two housings B and b, with cylindrical passages through them. The housings are arranged end to end with a space C between them and their axes in line. The space is bridged and the tops of the housings are connected by a block or table D, having the vertical central opening d. Upon the top of the table will be noted the cam end E of the operating lever or handle e. The function of the handle is to draw upwardly the clamping ring F by means of its stem f, to which the cam end E of the lever is pivotally secured.

As best shown in Figs. 1 and 3, a trunnion

pin G passes through the passages in the housings and through the ring, and it will be readily seen that when the clamping ring is drawn upwardly and held against the pin 60 it is firmly fixed in the housings against rotation or other displacement. The pin G is secured to the hub g of the triangular carrier plate H. The form of this plate usually employed in practice is set out in Figs. 1 and 65 2. This form is specially applicable to the cylinder blocks of the Ford motor. It is not intended, however, to limit this invention to the specific shape of carrier illustrated. In Fig. 2 it will be observed that the carrier H 70 has a relatively wider top portion having the short cylindrical projecting portions J and j, pierced by bolt holes as set forth, and the relatively narrow lower end provided with the pin or stud h.

The cylinder block of the Ford automobile is provided at the sides of the opening to which the conduit for the cooling water from the radiator is attached, with bolt holes such as the threaded hole K shown in 80 Fig. 1, and the screws k used with this invention are threaded to engage those holes in the Ford cylinder block. Similarly, the block L has a flange M pierced by a number of spaced holes, with one of which the stud 85 h is shown in engagement in Fig. 1.

In the operation of this invention it is desired not only that the cylinder block be supported, but, that it shall be strongly and rotatively held upon the bench, in order that 90 any necessary work may be performed upon it, and that it may be caused to assume any position convenient for the workman. It is believed to be readily discernible from Fig. 1 that, if the handle or lever e be turned upwardly, the clamping ring F will be lowered and the trunnion pin G may be rotated in the two housings and clamped in any adjusted position. As the pin G is secured to the carrier H, and the block L to the carrier, 100 the block is correspondingly rotated and adjusted.

Having now described this invention, and explained the mode of its operation, what I claim is:

1. In a cylinder block holder, the combination with a base, of housings erected upon said base and having passages through them, the said housings being arranged with a space between them, a block or table connecting the said housings at the tops thereof, a clamping ring movable in said space, said

ring having a stem passing upwardly through the table, means acting upon the table for drawing the ring upwardly, a trunnion pin passing through the ring and the 5 passages of the housings, and a carrier attached to the pin.

2. In a cylinder block holder, the combination with a base, of housings erected upon the said base and having passages through 10 them, the said housings being arranged with a space between them, a clamping ring movable in the said space, said ring having a vertical stem, means acting upon the housings for drawing the ring upwardly, a trunnion 15 pin passing through the ring and the passages of the housings, and a carrier attached to the pin.

3. In a cylinder block holder, the combination with a base, of housings erected upon 20 the base having passages through them, the said housings being arranged with a space

between them, a block or table connecting the said housings upon the top thereof, a clamping ring movable in the said space, said ring having a vertical stem passing 25 through the table, and a lever having a cam end engaging the said stem and acting upon the table to draw the ring upwardly, a trunnion pin passing through the ring and the 30 passages of the housings, and a carrier attached to the said pin.

4. In a cylinder block holder, the combination with a carrier having a relatively wider top and a narrower bottom end, the said carrier having portions at the top provided 35 with separated bolt holes, and having a projecting pin at the said narrower end, and a trunnion pin projecting from the said carrier between its ends.

In testimony whereof I affix my signature. 40

GEORGE J. S. COLLINS.
